UNITED STATES PATENT OFFICE.

ANTON DROHOMIREZKI, OF DETROIT, MICHIGAN.

SHIP-PROTECTOR.

1,263,538.

Specification of Letters Patent.

Patented Apr. 23, 1918.

Application filed November 19, 1917. Serial No. 202,807.

To all whom it may concern:

Be it known that I, ANTON DROHOMIREZKI, a subject of the Emperor of Austria, residing at Detroit, in the county of Wayne 5 and State of Michigan, have invented certain new and useful Improvements in Ship-Protectors, of which the following is a specification.

My primary object of the invention is to 10 provide a device to be carried by ships for protecting the same against oncoming torpedoes, the device being adjustable for positioning so as to offer no obstruction to the ship while docking and very little obstruction 15 to the travel of the ship through the water.

A further object is to provide a protector for ships' hulls that is light in weight, easy to manufacture and quickly installed upon a 20 ship, and which will serve, when in operative position, to intercept a torpedo in its travel and prevent the same striking the hull of the ship.

A still further object is the provision of 25 a shielding member for ships' hulls arranged for catching torpedoes, adjustable to an inoperative position when not in use and tiltable to different inclinations when desired, for presenting different forms of engaging 30 surfaces to the oncoming torpedoes.

In the drawing forming a part of this application and in which like designating characters refer to corresponding parts throughout the several views,

35 Figure 1 is a side elevation of the device. Fig. 2 is a vertical transverse sectional view thereof.

Fig. 3 is an enlarged side elevational view of a portion of the same, and

40 Fig. 4 is a perspective view of a portion thereof.

My protector is adaptable for installation upon the hull of any form of ship and is herein illustrated in connection with a ship 45 having a hull 11 provided with a deck 12, a cabin 13 being positioned upon the deck, a pilot house 14, funnels 15 and a wireless outfit 16.

Most encounters with the torpedoes of submarines being from opposite sides of the hull, a screen 17 having upright posts 18 is swingingly suspended from the outer edge 19 of an overhanging ledge or plate 20 projecting from opposite sides of the deck 12.

55 Chains 21 are connected between the posts 18 thereby forming substantially rectangular

meshes adapted to receive a torpedo for holding the same against striking the hull 11. The meshes of the screen 17 are of suitable size for preventing a torpedo from passing therethrough, and one of the screens is positioned at each side of the hull and extends above and below the water line for intercepting a torpedo traveling well below the surface of the water.

The screens 17 normally depend vertically as best illustrated in Fig. 2 of the drawing and a plurality of shifting levers 22 is arranged for each screen 17, pivoted to racks 23 upon the plates 20 and extending through 70 perforations 24 in the plates for pivotal connection by means of links 25 with a longitudinally extending bar 26 carried by each of the screens 17. Retainers 27 are provided for the levers 22 for engaging the rack 23 75 when the levers are suitably adjusted for positioning the screen 17 as found desirable. The bars 26 are secured to lugs 29 upon spaced ones of said posts 18, while the intermediate posts are only connected by the 80 chains 21.

By moving the levers 22 outwardly, the screen 17 will be swung inwardly with the lower curved ends 28 of the posts 18 engaging the adjacent side of the hull 11 as 85 indicated by dotted lines in Fig. 2. The screen 17 still affords a protection for the hull 11 when so positioned inwardly, but is so positioned ordinarily to permit the ship 10 to approach in close proximity to a wharf 90 or landing, at which times the plates 20 are also serviceable in loading and unloading the cargo. By moving the levers 22 inwardly, the screens 17 will be forced outwardly and it will be seen that when the 95 screens are inclined in either direction, they will depend a lesser distance beneath the surface of the water, but will position the chains 21 and bars 26 in closer vertical spaced relations, a torpedo being readily 100 caught and held by the screens when so positioned.

The screens 17 whether operatively or inoperatively arranged present only slight obstruction to the movement of the ship 105 through the water. The sailors upon the deck 12 may readily shift the screens 17 to desired positions by means of the levers 22 while the retainers 27 will maintain the screens so adjusted.

110
What I claim as new is:—

1. A ship protector comprising outwardly

projecting plates carried by the deck of the ship, screens swingingly depending from the outer edges of the plates having open meshes adapted for receiving and holding torpedoes, adjusting levers pivoted through said plates operable from points thereabove, and link connections between the said levers and screen.

2. A protector for ships' hulls comprising oppositely arranged plates outwardly projecting from the hull of a ship upon the level of the deck thereof and provided with perforations, spaced posts hinged to the outer edges of the plates, a plurality of connecting chains arranged between said posts, levers pivoted to said plates projecting through said perforations, longitudinally extending bars carried by said posts, link connections between the lower ends of said levers and said bars whereby the outward movement of the levers inwardly inclines

the said posts with their lower ends engaging the sides of the hull, and adjustment retaining means for the said levers.

3. A protector for ships comprising an outwardly projecting plate carried adjacent the top of the hull, a plurality of posts pivotally depending from the outer edge of the plate, flexible spacing connections between the said posts forming torpedo receiving meshes between the connections and posts, inwardly projecting lugs carried by widely separated ones of said posts, a bar extending through said lugs positioned between the posts and the adjacent side of the hull, adjusting levers pivoted through said plate and links hinged to the lower ends of said levers and having pivotal connections with the bar adjacent said lugs.

In testimony whereof I affix my signature. 40

ANTON DROHOMIREZKI.
